CLAIM

I claim the ornamental design for the post planter, as shown and described.

DESCRIPTION

FIG. 1 is a perspective view of the post planter of a first embodiment;

FIG. 2 is a front view thereof;

FIG. 3 is a back view thereof;

FIG. 4 is a top view thereof;

FIG. 5 is a bottom view thereof;

FIG. 6 is a side view thereof;

FIG. 7 is a side view thereof showing the side opposite that shown in FIG. 6;

FIG. 8 is a perspective view thereof of the back view;

FIG. 9 is an alternate back view of FIG. 8 of a second embodiment.

FIG. 10 is a perspective view of the post planter of a third embodiment;

FIG. 11 is a front view thereof;

FIG. 12 is a back view thereof;

FIG. 13 is a top view thereof;

FIG. 14 is a bottom view thereof;

FIG. 15 is a side view thereof;

FIG. 16 is a side view thereof showing the side opposite that shown in FIG. 15; and,

FIG. 17 is a perspective view thereof of the back view.

The broken lines shown in the drawing are for illustrative purposes only and form no part of the claimed design.
